UNITED STATES PATENT OFFICE.

WILLIAM W. LEWIS, OF SEATTLE, WASHINGTON.

DESIGN FOR A BOTTLE.

56,983.

Specification for Design.

Patented Jan. 25, 1921.

Application filed January 5, 1920. Serial No. 349,618. Term of patent 3½ years.

To all whom it may concern:

Be it known that I, WILLIAM W. LEWIS, a citizen of the United States, whose post-office address is 314 Pike street, Third avenue, in the city of Seattle, county of King, and State of Washington, have invented a new, original, and ornamental Design for a Bottle, of which the following is a specification, reference being had to the accompanying drawings, forming a part thereof.

The figure is a front perspective view of a bottle for fruits of various kinds showing my new design.

I claim:

The ornamental design for a bottle as shown.

WILLIAM W. LEWIS.
